UNITED STATES PATENT OFFICE.

LUTHER S. ELLETT, OF MILBURN, OKLAHOMA.

SPARK PLUG.

Application filed March 12, 1925. Serial No. 15,064.

This invention relates to spark plugs and contemplates a plug of novel construction wherein the electrodes can be conveniently adjusted without removing the plug from the motor, and one wherein the various parts can be easily cleaned as the occasion may require.

Another object of the invention resides in the provision of a spark plug designed to facilitate priming of the engine in cold weather, and one wherein the electrodes can be viewed without removing the plug from the engine, or without stopping the engine, when it is desired to know whether or not the plug is operating properly.

Other objects and advantages of the invention will be better understood when the following detailed description is read in connection with the accompanying drawing, the invention residing in the construction, combination and arrangement of parts as claimed.

In the drawing forming part of this application, like numerals of reference indicate similar parts in the several views, and wherein:

Figure 1 is a vertical sectional view through the plug constructed in accordance with the present invention.

Figure 2 is a sectional view taken on line 2-2 of Figure 1.

Figure 3 is an end elevation.

Figure 4 is an end elevation.

Figure 5 is an end elevation of one of the nuts arranged within the plug.

Figure 6 is a perspective view of the washer.

Figure 7 is a plan view of the nipple.

Figure 8 is a view in elevation thereof partly broken away.

Figure 9 is a vertical sectional view through a modified construction.

The spark plug forming the subject matter of the present invention is patterned after a pet cock of well known construction, and includes a tapered body portion 10 which is formed with depending hollow boss 11 into which is threaded the adjacent end of a nipple 12 as shown in Figure 1. This nipple 12 is formed with a flange 13, preferably of the outline shown in Figure 7 and which engages the boss 11 when the nipple is properly associated with the latter. The nipple 12 is of course threaded for proper association with the spark plug opening of the engine with which it is intended to be used.

Arranged within the body portion 10 of the plug is a correspondingly tapered sleeve 14 which is interiorly threaded adjacent the opposed ends thereof for a purpose to be presently described. Threaded into one end of this sleeve is a nut 15 which is formed with a longitudinal bore opening at both ends to receive an electrode 16, the point of which projects beyond the inner end of the nut in axial alignment with the electrode 17 of the spark plug indicated generally at 18 in Figure 1. The part 18 is of course insulation. This spark plug 18 is of the usual construction and is adapted to be received by a nut 19 threaded within the sleeve 14, and also passed through an opening in the nut 20 which also enters one end of the sleeve 14 as shown in Figure 1. The adjacent ends of the nuts 19 and 20 respectively are slightly dished or recessed to accommodate the packing 21, the packing being arranged at opposite sides of the flanges 22 forming part of said plug, so that when the nut 20 is tightened, the plug 18 is held fixed relatively to the sleeve 14. Now, it will be noted upon inspection of Figure 1 that the electrode 16 is threaded for a portion of its length as at 23 so that this electrode can be adjusted toward and away from the electrode 17 providing a proper gap therebetween, and that one end of the electrode 16 is squared as at 24 to permit the use of an ordinary wrench for adjusting the electrode as will be readily understood. A nut 15 is formed, with a flange 25, and after the nut has been associated with the sleeve 14, this flange is used in conjunction with a resilient washer to hold the sleeve properly associated with the body portion 10 of the plug. This washer is preferably of the construction shown in Figure 6 and indicated at 27 and wherein it will be noted that the washer includes a plurality of coils, from one of which extends a right angularly disposed arm 28 which is provided with an opening 29 to receive the fastening element 30 which is utilized to secure the washer in its entirety fixed with relation to the body portion 10 of the plug. The operative arrangement of this washer is shown in Figure 1, wherein it will be noted that the convolutions 27 are arranged between the adjacent end of the body 10 and the flange 25 of the nut 15, these convolutions exerting a compressive force 110 against the flange to draw the sleeve 14 in one direction through the body portion 10

and hold it in position for use. While the sleeve is held stationary with relation to the body 10, while the plug is in use, through the instrumentality of the washer just described, the sleeve 14 is permitted rotation so that it can be turned within the body portion for a purpose to be hereinafter described. The nut 15 is formed with a squared portion 31 to accommodate a suitable wrench when it is desired to turn the sleeve within the body portion. If desired, the sleeve may be provided with an additional point or electrode 32 which projects inwardly from the sleeve at a right angle to the electrodes 16 and 17 respectively, and they occupy a position in align with the space between said electrodes, or can be easily flexed in either direction as indicated by dotted lines in Figure 1. It will be noted from the construction shown and described, that the electrodes 16 and 17 are arranged in a horizontal plane, with the electrodes 16 susceptible of quick adjustment to vary the space between the electrodes as the occasion may require, and by reason of the general construction, this can be accomplished without removing the plug from the motor, and also while the engine is in operation. Any of the various parts can be quickly removed from the body of the plug to be cleaned or repaired, or replaced. Then again, if it is desired to look at the plug to determine whether or not the latter is operating properly, it is only necessary to turn the sleeve 14 within the body portion 10 to position the opening 33 of the sleeve in align with the opening 34 in the body of the plug, whereupon the user can look into the interior of the sleeve directly at the electrodes 16 and 17 respectively. When the plug is in use, the sleeve 14 occupies the position shown in Figure 2, wherein it will be noted that the opening 33 of the sleeve is in align with the nipple 12, the fuel passing upwardly through the nipple into the plug to be ignited. It is sometimes necessary to prime an engine in cold weather, to facilitate starting of the engine, and this duty requires the removal of the plug as will be readily understood. The present invention makes it possible to prime the engine without removing the plug and is accomplished by simply turning the sleeve 14 within the body portion 10 to bring the openings 33 and 34 into registration with each other, whereupon gasoline can be poured into the sleeve, and the latter subsequently returned to its normal position. The invention is very simple in construction and particularly advantageous for the purpose intended. It is to be understood that the nipple 12 may be inter-

changed with the nut 15, thereby changing the plug to a vertical position by properly adjusting the electrode 16 with relation to the nut 15, and the electrode 17 and that the body portion 19 may be rotated around the sleeve 14 for the purpose of cleaning and inspection of the electrodes 17 and 32.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

1. A spark plug comprising a body portion tapered toward one end and having an opening in one side thereof, a tapered sleeve arranged within the body for both rotary and sliding movements, and having an opening adapted to be moved into and out of registration with the opening in said body, an insulated member arranged centrally in said sleeve and supported at one end thereof, an electrode projecting from said insulating member, an additional electrode supported in spaced relation to the first mentioned electrode, a nut threaded into one end of the sleeve, a flange formed on said nut, and a resilient washer secured to said body portion and including a plurality of convolutions interposed between one end of the body and said flange of the nut, whereby end thrust is exerted upon the sleeve for holding it frictionally in proper position within the body.

2. A spark plug comprising a tapered body, a tapered sleeve arranged within the body for both rotary and sliding movements, said sleeve and body having openings in the sides thereof, an insulated member arranged in one end of the sleeve and supported thereby, an electrode projecting from said member, a pair of additional electrodes arranged adjacent the first mentioned electrode, one of said additional electrodes being adjustable with relation to the electrode carried by said insulated member, a nut threaded into one end of the sleeve, a flange carried by said nut, and a resilient washer secured to said body portion and including a plurality of convolutions interposed between the body portion and flange of said nut, whereby an end thrust is exerted upon the sleeve for holding it in proper position by frictional contact with the body portion.

In testimony whereof I affix my signature.

LUTHER S. ELLETT.
